UNITED STATES PATENT OFFICE.

ALEXANDRE PICARD, OF MONTAIGN, FRANCE.

BREECH-LOADING FIRE-ARM.

SPECIFICATION forming part of Letters Patent No. 253,422, dated February 7, 1882.

Application filed March 16, 1880. (No model.) Patented in France February 3, 1879.

To all whom it may concern:

Be it known that I, ALEXANDRE PICARD, of Montaign, Jura, France, have invented Improvements in Breech-Loading Fire-Arms; and I do hereby declare that the following is a full, clear, and exact description of the same, reference being had to the annexed sheets of drawings, making a part of the same.

My invention relates to that class of fire-arms in which the bore is closed when the cartridge is in the barrel by means of a block or rocking block which is brought in position before the explosion of the cartridge.

My improvements consist chiefly, first, in the improved construction of the rocking block, which is made in one piece with the hammer, the said block working automatically in its downward movement, and the extractors being placed on both sides of the frame.

In accompanying drawings, Figure 1 is partly a side view and partly a longitudinal section of the breech and lock portion of my improved gun, the combined breech-block and hammer being shown thrown back ready for firing. Fig. 2 is a longitudinal central section of the lock and breech, the combined breech-block and hammer being shown closed. Figs. 3, 4, 5, 6 are detail views of parts detached. Figs. 7, 8, 9 are detail views.

A is the breech of the gun, having a rear extension, *a*, provided with a lengthwise slot, in which is placed the rocking block B, which in its movement rotates on a rib, *a'*. The rocking block B (shown detached in Fig. 5) has plates *b* attached to its central part, which plates have V-shaped projections *b'* at the front end. The object of these projections is to work the extractors *u*, as will be hereinafter described. Said plates *b* can be easily removed when the projections *b'* are worn. The rocking block B has upon its upper face a recess, which allows the cartridge to pass into the barrel. In this recess is fitted a small plate, *d*, Fig. 2, mounted upon a pivot-pin, *d'*. The free forward end of plate *d* is pressed upward by a spring, *e*, placed in a recess beneath it, and by this means the end of the plate *d* is caused to project somewhat above the upper face of the block B, thus preventing the cartridge placed in the barrel from dropping back when the breech is open.

A lever, *f*, is formed solid with the block B, and the latter has in its rear extremity a hole that receives a screw, *g*, on which the sear or catch *h* is pivoted. A spring, *i*, forces the front end of the catch *h* downward, and the rear end has a hook, *h'*, which is adapted to engage a corresponding hook, *j*, in the end *a'* of the breech A.

The contact portion or surface of the hook *j* is formed of a plate that can be easily removed and changed when worn.

The conical hammer *l* is made in one piece with the block B, so that if the block is suddenly pushed upward the hammer will strike 65 the cartridge through a hole made in the barrel and thereby explode it.

In order to give the block B and its hammer *l* the required sudden movement, I employ a forked spring, *n*, Fig. 7, whose free ends rest 70 on pins *m*, projecting from both sides of the block B. The spring *n* is fixed below the barrel by means of a hand-screw, *n'*, Fig. 1. By this means, when the mechanism is in the firing position, Fig. 2, if the trigger *o* is pressed 75 upward the head of the said trigger forces the hook of the catch *h'* out of the hook *j* of the breech, and the block B is thrown suddenly upward by the action of the spring *n*, so that the cartridge is struck by the hammer *l*, as above 80 mentioned, and exploded.

The guard-plate *p* is provided with two rectangular slots, *q* and *r*, the larger one, *q*, for the lever *f*, and the smaller one for the trigger *o*. The plate *p* is clamped in place by means of 85 hand-screws *s* and *s'*, Fig. 1, passing through the stock of the gun and screwing into the breech A. In order to avoid any vibration, the ends of the plate *p* are bent downward, so that when in position the plate may act as a spring, 90 pressing and holding the gun firmly upon its stock *t*.

The curved arms of hand-screws *s s'* protect the lever *f* and the trigger *o* from external blows, so that the ordinary guard may be dispensed with. Besides, the screw *s'* is provided with a flat end, *s''*, which is used as a screw-driver for the small screws of the mechanism. This disposition allows the gun to be taken to pieces without aid of any tool.

The extractors are placed on both sides of the barrel. Each of them is a plate, *u*, pro-

vided with a concavity, u' , in its inner face, which concavity corresponds to the bore of the barrel. The extractors are loosely mounted upon screws passing transversely through them, and their lower ends, u^3 , are provided with projections, as shown. In the downward motion of the block B the projections b^2 , made thereon, will press upon the lower toes, u^3 , of the extractors u , and, tilting them, force their upper parts to project outward, as shown in Fig. 1, thus drawing and throwing the shell out of the gun. The extractors are put in motion only when the barrel is open; and, besides, in order to give them a more effective action, a sudden motion is imparted to lever f , causing the block B to swing down farther than shown in Fig. 1. After the projection of the shell out of the gun the spring i of the tumbler brings again the block B into the firing position, Fig. 1.

I propose to use with this gun a bayonet-sword having saw-teeth on its back. It is fixed on the end of the barrel by means of two shoulders and a spring in the hilt.

What I claim as new is—

In a breech-loading gun, the combination of the rocking spring-actuated block B, having a hammer or piercing-point, l , made in one piece and provided with lever-arm f , the catch or sear h , pivoted to the rear portion of the breech-block, a fixed claw or shoulder, j , on the breech-piece, and the barrel having a hole in its under side to receive the hammer-point, as shown and described.

ALEXANDRE PICARD.
